UNITED STATES PATENT OFFICE.

GEORGE P. CRYSLER, OF CHICAGO, ILLINOIS.

GRATE STRUCTURE.

1,369,883.

Specification of Letters Patent.

Patented Mar. 1, 1921.

Application filed April 12, 1919. Serial No. 289,671.

To all whom it may concern:

Be it known that I, GEORGE P. CRYSLER, a citizen of the United States, residing at Chicago, in the county of Cook and State of Illinois, have invented certain new and useful Improvements in Grate Structures, of which the following is a specification.

The invention relates to improvements in grate structures and has especial reference to structures of this character for steam boilers, or the like.

To effect the highest economy in consumption of fuel, the grate area of the furnace must bear an efficiency ratio to the several variable factors, unknown in many instances, until after the installation of the plant, of which the furnace is a part. In some installations 10 to 30 pounds of coal per square foot of grate surface area must be consumed per hour in order to realize the maximum capacity of the associated boiler, while in other situations, where the periods of firing are of less frequent intervals, such for example, as in house heating boilers, the fuel consumption per square foot of grate area per hour is frequently as low as 3 to 4 pounds of coal.

In the exigencies of firing operation the fire must at times be reduced to meet other conditions, in which case, with unchanged grate area, the ratio of air supplied to or passing through the grate becomes out of proportion to other factors because of the reduced air resistance resulting from a thinner fuel bed imposed upon the grate surface. A poor quality of coal requires more grate surface than coal of greater thermic value; the intensity of the draft, also, has a modifying effect upon the size of the grate best adapted to produce the most efficient conditions of operation and other variants disturb the co-operative equilibrium that has been established for maximum service.

The object of the present invention is to provide means for conveniently and quickly reducing the effective grate areas.

Another object is to vary the size or area of the draft throat, between the bridge wall and the boiler coincidentally with a change in grate area.

Other, further and more specific objects of my invention will become readily apparent, to persons skilled in the art, from a consideration of the following description when taken in conjunction with the drawings, wherein:—

Figure 1 is a longitudinal section, showing a boiler in elevation and furnace with my improvement incorporated therein.

Fig. 2 is an enlarged, fragmentary section 60 of the movable bridge wall which is adapted to be moved toward the firing door for decreasing the effective area of the grate and gas throat.

Fig. 3 is a section taken on line 3—3 of 65 Fig. 2.

Fig. 4 is a section taken approximately on line 4—4 of Fig. 2.

Fig. 5 is part of the metal frame work of the bridge wall.

In all the views the same reference characters are employed to indicate similar parts.

In the physical embodiment, in the drawings of which I have shown my improved structure, A is a boiler; B is the furnace; C 70 is the smoke flue behind the furnace. 10 indicates the grate bars of the grate, which are set, preferably, slightly inclined, from their outer ends, inwardly and downwardly, as shown in Fig. 1. 11 is the foundation for 80 the movable bridge wall 12.

In Fig. 1, the movable bridge wall 12 is in position which it occupies when all of the grate surface is in effect. The bridge wall 12 is adapted to be moved forward over 85 the grate by the lever 13, to the position shown in dotted lines, in which position the bridge wall covers that part of the grate which is thus made inoperative, thereby reducing the effective area of the grate. The 90 bridge wall is preferably made of an iron framework, a fragment of which is shown in Fig. 5, in which there is contained a plurality of inverted channel bars 14, joined together, as at 14', by rivets that pass through 95 the upturned flanges of the channel bars. In the particular embodiment there are two and one-half such channel bars put together in this manner, as shown in Fig. 1. Extending across the front of the bridge wall 100 foundation structure 11, is an angle iron 15, upon which the inner ends of the grate bars rest and upon the upper surface of which rides the channel bars 14, thereby preventing a draft of air from the ash pit 16 into the 105 smoke flue C under the movable bridge wall. Side plates 17 are joined to the upturned flanges of the channel bars 14 by angle braces 18. There is a plate 17 located at each end of the series of upturned channel 110 bars. At the front end of the reciprocatable bridge wall section, is a casting 19, pro-

vided with a series of downwardly and forwardly tapering spaced apart teeth 20, secured together by integral chaplets or lugs 21. The end tooth 22, at each end, is provided with a depression in which the tapered end 23 of the plate 17, is inserted, so that the outside surface of the teeth 22 and the outside surface of the plates 17 will be in the same longitudinal plane and substantially flush with the respective inner surfaces of the walls 24, of the boiler setting.

The casting 19 is provided near its top surface with a longitudinally extending, angular part 27, which extends longitudinally 15 of the casting 19, but transversely of the boiler setting, to receive a fire-proof structure 28, made, preferably, of the same material of which fire-bricks are composed, and preferably, molded in, or to fit the 20 frame, substantially as shown in Figs. 1 and 2.

Located on each side of the movable structure are rods, or bars 29, and 30, respectively, bolted to the upturned flanges of the 25 adjacent channel bar 14, as at 31. These bars pass down through spaces between adjacent grate bars and are deflected forwardly toward the center of the structure where they are held together, as at 32, uniting in 30 a bar 33 which extends forwardly and is connected to a vertical hand-operating lever 13, as at 34, so that when the lever is moved to dotted line position, shown in Fig. 1, the movable bridge wall structure is thereby 35 moved to its extreme forward position shown by the dotted lines. Extending through the structure 19, parallel with the grate surface 10, is a shaft 35 that passes through the bars 29 and 30, as at 36, and finds bearings 40 therein. Near each of the bars 29 and 30, at this point, is a roller 37, mounted on the shaft and adapted to roll over the top of the grate surface, consisting of the grate bars 10. In the rear of the angle iron 15, on the foundation 45 11 for the bridge wall, are a plurality of track bars 38 having their upper surfaces in substantially the same horizontal plane as the upper surface of the angle bar 15, and upon which the shiftable bridge wall is longitudinally movable.

The firing door 39 and the ash door 40 are provided, as usual, in structures of this character.

When it is desired to reduce the effective 55 surface of the grate in the furnace B it is only necessary to move the bridge wall section 12 forwardly, by pulling out the lever 13 into dotted line position, or to any intermediate point. As the bridge wall moves 60 forwardly the throat 41, for the hot prod-

ucts of combustion, is reduced in vertical dimensions and has the effect to maintain, practically, substantially constant the velocity of the gases proportional to the firing grate surface area other conditions remaining unchanged. As the structure 12 is moved back, on account of the inclination of the path in which it is moved the throat 41 is enlarged in dimension, as clearly shown by comparison of the dotted outline 65 with the full line structure, thereby increasing the throat area to accommodate the increased flow of hot gases from the combustion produced within the furnace.

In installing a plant, in accordance with 75 my invention, it is the policy of wisdom to make the grate surface amply large for the largest demands and then contract the area of the surface in the manner described to harmonize with other conditions of operation.

When a bed of coal is packed up on the front end of the structure 19, or on the teeth thereof, air will pass into the said bed of coal from the openings between the teeth 85 therebelow and thereby increase the oxidizing effect of the fuel at the point of most intense combustion, or at the point where the products of combustion pass out of the furnace over the top of the bridge wall. 90 The air that passes through the toothed structure 20 suffices to keep it sufficiently cool to prevent melting by the intense heat developed in the furnace.

While I have herein shown a single embodiment of my invention, for the purpose of clear disclosure, it will be manifest, to persons skilled in the art, that considerable variation may be made in the configuration and general disposition of the parts, within 95 the scope of the appended claim.

Having described my invention, what I claim is:—

A device of the character described having parallel grate bars; a movable bridge 105 wall supported on the grate bars; means extending below the grate bars and forwardly of the grate to move the bridge wall; a metallic front for the bridge wall comprising a series of downwardly and forwardly inclined spaced-apart teeth, substantially registering in vertical planes with said grate bars to provide air conducting spaces between said teeth and rollers back of the teeth upon which the front end of the bridge wall 110 is supported.

In testimony whereof I hereunto subscribe my name.

GEORGE P. CRYSLER.
